TO CRESCENT MANUFACTURING COMPANY, OF SCOTTDALE, PENNSYLVANIA, A CORPO-
RATION OF PENNSYLVANIA.

ADJUSTABLE COLLAPSING TAP.

No. 909,749.

Specification of Letters Patent.

Patented Jan. 12, 1909.

Application filed February 5, 1908. Serial No. 414,879.

To all whom it may concern:

Be it known that we, FREDERICK L. BROWN and ISAAC W. SPRINK, citizens of the United States, both residing at Scottdale, in the county of Westmoreland and State of Pennsylvania, have invented certain new and useful Improvements in Adjustable Collapsing Taps, of which the following is a specification.

10 This invention relates to metal working tools, and more particularly to that type of tools known as taps, and designed for cutting threads in nuts and sockets of different articles, such for instance as the threaded 15 couplings and connections used in uniting steam, gas, water, and other piping, although it will be understood that the improved construction of tap claimed herein is capable of general use for threading holes.

20 In carrying out the present invention, the same has in view the provision of a simple and thoroughly practical construction of tap of the collapsing type, that is, wherein the threaded chasers or cutting dies are adapted 25 to be held in expanded operative positions during the threading operation, and then retracted or collapsed when a thread of any predetermined length has been cut. In this connection, one of the main objects of the 30 invention is to provide a collapsing tap comprising positive and reliable means whereby the threaded chasers are automatically retracted or collapsed from the work, or released from their operative positions, so that 35 the cutting or threading operation can be automatically arrested when the tap has reached the proper depth in the work.

A more general object of the invention is 40 to provide a tool of the character indicated, which possesses extreme simplicity of construction combined with the utmost efficiency in operation, the arrangement for expanding and collapsing the chasers is such that its action is absolutely positive, while at the 45 same time the chasers are afforded a solid seat or shoulder throughout their entire lengths so as to be rigidly supported against the action of cut. In this phase of the invention, the same contemplates a construction 50 which avoids the objection to the chasers "floating" in the tool stock or holder, as is common to some taps of this character.

A further object of the invention is to provide a strong and positive locking device

for holding the parts set when the chasers 55 are expanded to operative cutting positions, and also to provide a general combination of parts which can be readily handled and easily understood by the ordinary mechanic or operator, which is a feature of practical 60 importance in machine shop practice.

Another object of the invention is to provide an adjustable collapsing tap adapted for use on turret lathes, or on drill presses, either stationary or on a live spindle, and in 65 fact adapted to be operated with any of the ordinary machinery and with tapping tools.

Another object of the invention is to provide an adjustable collapsing tap wherein the various members are compactly and securely mounted on the tool stock, while at 70 the same time being readily assembled and disassembled.

With these and many other objects in view, which will more readily appear as the 75 nature of the art is better understood, the same consists in the novel construction, combination, and arrangement of parts herein-after more fully described, illustrated, and claimed.

The essential features of the invention are necessarily susceptible to structural modification without departing from the scope thereof, but a preferred embodiment of the 80 invention is shown in the accompanying 85 drawings, wherein,—

Figure 1 is a perspective view of a collapsing tap constructed in accordance with the present invention. Fig. 2 is an end view thereof, showing the end body cap removed 90 to expose the interlocked feathered connection between the chasers and the taper plug of the operating plunger therefor. Fig. 3 is a longitudinal sectional view of the tool. Fig. 4 is a similar view of the tool, the line 95 of section being at right angles to the line of section of Fig. 3. Fig. 5 is a perspective view of the tool stock, with all detachable parts removed therefrom. Fig. 6 is a detail in perspective of the end body cap. 100 Fig. 7 is a perspective view of the operating plunger showing two of the threaded chasers detached therefrom. Fig. 8 is a detail view of the retracting spring and retaining nut associated with the longitudinally movable 105 operating plunger for the chasers. Fig. 9 is a detail in perspective of the adjustable knock-off device for retracting the operating

2
plunger, and hence the chasers therewith. Fig. 10 is a detail in perspective view of the longitudinally slidable locking ring. Fig. 11 is a similar view of the rotatable cam ring. Fig. 12 is a detail in perspective of one of the thrust springs for closing the locking ring to a locking position, and thereby holding the cam ring against rotation. Fig. 13 is a detail sectional view on the line 13-13, at one side of the end retaining ring, and illustrating the stationary spring carrier for the auxiliary operating spring which assists in rotating the cam ring in the collapsing operation for the tool.

15 Like references designate corresponding parts in the several figures of the drawings.

The improved tap forming the subject matter of the present application, includes in its general organization a main body portion 1, which may be characterized as a tool stock. This tool stock is preferably of a tubular cylindrical formation and is provided in one end portion thereof with what may be termed a spring socket 2, and in its opposite end portion with an enlarged bore portion constituting what may be termed an enlarged working space 3 for one of the movable elements of the tool. Also, at one end, the tool stock 1 has formed therein a plurality of suitably spaced and longitudinally arranged die guiding slots 4 adapted to loosely accommodate therein the longitudinally disposed and radially shiftable chasers or dies 5. All of said chasers or dies 5 are of a general conventional form, each of the same consisting of a flat, approximately rectangular plate formed at its outer edge with the cutting threads 6 which are complements of the corresponding threads of the other chasers to form the complete tap for a threading operation. According to the present invention, the said chasers 5, in addition to their usual outer threaded cutting edges 6, are formed with inclined inner bearing edges 7, which therefore make the individual chasers of an inwardly tapering width, and said inclined inner bearing faces 7 are directly and slidably supported on the solid, flat, supporting seats 8 provided by the inclined flat sides of the cross sectionally angular taper plug 9. This taper plug 9 is formed integrally or rigidly with one end of a longitudinally movable operating plunger 10 slidably mounted within the longitudinal bore of the hollow tool stock 1, and having one end portion thereof lying within the spring socket 2, and the plug part 9 thereof slidably registering, at its major diameter, in the working space 3 of the tool stock, all of which is plainly shown in Fig. 3 of the drawings.

In connection with the mounting of the chasers, it is preferable to provide a feathered interlocking connection between the same and the taper plug 9, and this may be

conveniently and satisfactorily accomplished by forming the taper plug at one edge of each of its flat supporting seats 8 with an angular or hook shaped feathering rib 11 which slidably interlocks with a holding groove 12 formed longitudinally in one face of the chaser contiguous to its inner inclined edge 7, as may be seen from Figs. 2 and 7 of the drawings. While the connection described permits a relative longitudinal movement between the taper plug 9 and the individual chasers 5, thereby obviating the objection to the well known floating chasers, it will also be observed that the chasers take a solid seat upon the flat faces 8 of the taper plug and are therefore accurately supported at all points, besides being rigidly supported against the action of the cut.

The proper mounting and retention of the chasers and their operating element 9 is completed by the employment of a circular end body cap 13 screwed or otherwise detachably fastened upon the end of the tool stock carrying the chasers, and preferably provided at one side with an inturned cover flange 14 having a flush fit in the rabbeted seat 15 provided upon one end of the tool stock. The said cover flange 14 of the cap 13 is provided at intervals with clearance notches 16 registering with the die guiding slots 4 of the tool stock and providing clearance for the outer ends of the chasers.

It will be apparent that the longitudinal movement of the operating plunger 10 within the tool stock necessarily provides for expanding and collapsing the chasers 5 through their guiding slots 4, and the said plunger is placed under normal retracting spring pressure through the employment of a plunger retracting spring 17 housed within the spring socket 2 of the tool stock and bearing at one end against an inner bearing shoulder 18 within the tool stock, and at its other end against a terminal retaining nut 19, detachably screwed upon one extremity of the plunger 10.

In addition to the normal retracting spring pressure, the longitudinally movable operating plunger 10 is designed to have a direct coupled connection with a rotatable cam ring 20 which is rotatably mounted upon an intermediate bearing section 21 of the tool stock. The said section 21 is finished to provide an easy bearing for the rotatable cam ring 20, and the latter is preferably formed at one side thereof with a laterally projecting bearing collar 22, which collar has formed in diametrically opposite portions thereof, the inclined or oblique cam grooves 23, which respectively receive and engage the opposite end portions of the cross slide pin 24 which is fitted in the operating plunger 10 and projects beyond both sides of the latter so as to afford a direct operating and coupling connection between the

105

110

115

120

125

130

cam ring and the said plunger. Furthermore, it will be noted that the opposite end portions of the slide pin 24 are held to a rectilinear movement in the diametrically opposite longitudinally arranged pin guide slots 25 piercing and formed in the intermediate bearing section 21 of the tool stock, as best shown in Figs. 3 and 5 of the drawings. Aside from the pin-and-slot cam engagement between the cam ring and the operating plunger, the said cam ring is further provided on the external surface with the feathering keys 26 for the longitudinally slidable locking ring 27. Also the rotatable cam ring 20 is provided on its periphery with an offstanding operator's handle 28 and in one face thereof with a series of spring seats 29 accommodating therein one end of the spiral springs 30 which are interposed between the rings 20 and 27 so as to act in the capacity of thrust springs for normally pressing the locking ring 27 in a direction away from the cam ring 20 and hence in a direction for making and maintaining the lock hereafter more particularly referred to. It will be observed from the construction described, that the longitudinally slidable locking ring has a feathered connection with the element 22 of the cam ring, and hence is capable of an independent longitudinal movement toward and from the disk part of the ring 20, but has no independent rotative movement, being compelled to rotate with the cam ring 20 when the latter turns on its axis upon the bearing section 21 of the tool stock. In this connection, it will be observed that the locking ring 27 is provided in diametrically opposite edge portions of its center hole with the key ways or grooves 31, which loosely receive the feathering keys 26 of the cam ring. Inasmuch as the function of the ring element 27 is for locking purposes, the same is equipped with means for effecting the locking of the cam ring against rotation when the plunger 10 is advanced for expanding the chasers to their operative position. These means preferably consist of a pin block 32 loosely and adjustably mounted in a housing slot 33 formed in one side portion of the ring 27, said slot being sufficiently long to permit of an accurate adjustment and positioning of the pin block 32 therein. This pin block is provided at one side with a laterally projecting lock pin 34 which projects beyond the plane of one side of the ring 27 and is adapted to engage and disengage the hole in a keeper bushing 35 which preferably forms the lining of a keeper hole 36 provided in the fixed abutment ring 37 which forms an integral or rigid part of the tool stock. The mounting of the pin block includes a clamping bolt 38 extending through a slot 39 in the periphery of the ring 27 and

having its inner end engaging a threaded socket 40 in the body of the pin block 32. A washer 41 is interposed between the head of the bolt 38 and the periphery of the ring 27, and said bolt, when tightened, serves to 70 securely and rigidly clamp the pin block in its centered or adjusted position. This centering or adjusting of the pin block is preferably accomplished through the medium of a pair of aligned, but diametrically opposite adjusting screws 42, which are mounted in threaded openings 43 formed through the edge of the ring 27, as indicated by the dotted lines in Fig. 10 of the drawings. The arrangement and mounting of the screws 80 42 form a nice and accurate adjustment for the pin block 32, while the rigid clamping thereof is satisfactorily taken care of by the clamping bolt 38.

As a part of the mechanical equipment 85 for the cam ring 20 to assist in the rotation thereof, there is associated with such ring what may be termed a spring carrier 44 for an auxiliary operating spring 45 which aids in the function referred to. This 90 spring carrier is preferably in the form of a ring or disk arranged upon the tool stock at the outer side of the cam ring 20 and preferably rotatably adjustable on the tool stock so as to vary and maintain the compression of the said spring 45. This adjustable mounting of the spring carrier disk 44 may be conveniently accomplished by snugly arranging the same upon a smooth or unthreaded shoulder section 46 on the 100 tool stock, and fitting the said disk 44 with a pointed holding screw 48. The point of this screw is adapted to be engaged in any of a series of countersinks 49 provided in the shoulder section 46. It will be observed 105 that this construction admits of rotary adjustment of the carrier disk 44, but the latter is not permitted to have any end or longitudinal motion.

To provide for the proper mounting of 110 the auxiliary operating spring 45 in the stationary spring carrier 44, the latter has formed therein a spring housing slot 50, which slot is segmental in form and is provided at one end with a squared abutment 115 face or shoulder 51 against which bears one end of the spring 45, while the opposite end of said spring has a bearing against a fixed abutment 52 carried by the cam ring 20, and preferably in the form of a pin or stud projecting from the back face thereof. The said auxiliary operating spring 45 is a compression spring and is placed under working tension by the movement of the cam ring 20 in the direction for thrusting forward 120 the operating plunger 10, and hence expanding or opening the chasers so that when the said cam ring is unlocked or released, the force of the spring 45 is exerted in a direction to assist in rotating the cam ring back 130

ward, that is, in a direction for drawing back the operating plunger and thereby retracting or collapsing the chasers, as will be well understood from the foregoing 5 description.

The assembly of the parts immediately associated with the cam ring 20 and the locking ring 27 is completed by means of an end retaining ring 53 secured upon the 10 threaded shoulder 47 of the tool stock at the back of the ring or disk constituting the stationary spring carrier 44.

The knock-off or release of the chasers from the work is effected through the employment of an adjustable knock-off device 54 consisting of a strike head 55 in ring form, and the oppositely arranged angle carrying arms 56. The ring strike head 55 encircles that portion of the tool stock carrying the chasers 5 and is adapted to come in contact and frictionally engage with the work when the limit of the threading operation has been reached. The angle carrying arms 56 are rigidly connected to opposite 20 portions of the strike head 55 as at 57, and the parallel members of the opposite arms 56 are provided therein with longitudinally disposed adjustment slots 58 which receive the binder screws or bolts 59 engaging in 25 threaded sockets 60 provided in the periphery of the locking ring 27 at diametrically opposite points, and at the places where the threaded sockets 60 are located, the edge of the locking ring 27 has formed therein the 30 angular or equivalent shaped seats 61 which admit of the longitudinal adjustment of the arms 56, while at the same time they hold the same against lateral deflection or movement. Similar seats 62 are provided in diametrically opposite edge portions of the cam ring 20 to receive and brace the slotted portions of the arms 56, and this connection between the said arms and the cam ring also assists in holding the cam and locking ring 40 for rotation together, though not interfering in the least with the independent longitudinal sliding movement of the locking ring.

In the use of the tool, when the same is 50 to be put into operation, the operator's handle 28 of the cam ring is grasped and pushed forward, that is, in a direction for advancing the operating plunger 10 in a direction for causing the taper plug 9 to expand the threaded chasers outward through the guiding slots 4 therefor. The rotation of the cam ring in said direction also carries the locking ring to a position which brings the lock pin 34 thereof opposite the keeper 55 of the fixed abutment ring 37. When 60 this occurs, the thrust springs 30 come into play and slide the locking ring forward with the result of carrying the lock pin 34 into rigid locking engagement with the fixed 65 abutment ring 37, thus securely holding the

cam ring, as well as the operating plunger 10, locked in position for holding the chasers expanded in their operative threading positions, such chasers at the same time having a rigid support on the supporting bases or 70 seats 8 of the taper plug 9.

When the tool is run into the work, the threading operation continues until the face of the work comes in contact with the strike head or ring 55 of the knock-off device, and 75 the continued pressure of the tool against the work causes the knock-off device to slide the locking ring backward so as to disengage the locking pin thereof from the fixed abutment ring. This action releases the cam 80 ring so that through the combined friction of the work against the knock-off device, and the force of the auxiliary operating spring 45, the cam ring 20 is revolved in a direction which draws back the operating 85 plunger and consequently retracts or collapses the chasers and releases the tool from the work without need of reversing the tool, work, or machine.

From the foregoing, it is thought that the 90 construction, operation, and many advantages of the herein described collapsing tap will be apparent without further description, and it will be understood that various changes in the form, proportion, and minor 95 details of construction may be resorted to without departing from the spirit or sacrificing any of the advantages of the invention.

We claim:

1. In a collapsing tap, a tool stock having 100 a fixed abutment and carrying radially shiftable threading chasers, a rotatable cam ring operatively connected with the chasers, a spring-pressed locking device slidably interlocked with the cam ring and having an 105 engagement with said fixed abutment, and a knock-off device connected with said locking device, and comprising means for disengaging the locking device from the abutment, and also, by friction with the work 110 providing for the backward rotation of the cam ring.

2. In a collapsing tap, a tool stock having 115 a fixed abutment ring and carrying radially shiftable threading chasers, a rotatable cam ring operatively connected with the chasers, a spring pressed locking ring having a slideable feathered connection with the cam ring and adapted to have a locking engagement with said fixed abutment of the tool stock, 120 and a work engaged knock-off device connected to, and movable with, the locking ring.

3. In a collapsing tap, a tool stock carrying 125 radially shiftable threading chasers and provided with a fixed abutment element, a rotatable cam ring operatively connected with the chasers, a spring pressed locking ring operating between the cam ring and abutment element, said locking ring having a slideable feathered connection with the cam 130

ring and provided with a lock pin adapted to engage said fixed abutment element, thrust springs carried by the cam ring and arranged at one side of the locking ring for advancing the latter, and a work engaged knock-off device connected to, and movable with, the locking device.

4. In a collapsing tap, a tool stock carrying radially shiftable chasers and having a fixed abutment, a rotatable cam ring operatively connected with the chasers, a spring carrier ring held to the stock, an auxiliary operating spring carried by said carrier and arranged to assist the rotation of the cam ring in a backward direction, a locking

device rotatable with and slidable on the cam ring and engaging said abutment, and a work engaged knock-off device connected with the locking device for releasing the latter and also arranged to provide, through friction with the work, for rotation of the cam ring in a backward direction. 20

In testimony whereof we hereunto affix our signatures in the presence of two witnesses.
